CORROSION RESISTANT LIQUID HYDROCARBONS CONTAINING MIXTURE OF ALKYL SUCCINIC ACID AND POLYAMINE SALT THEREOF

James R. Miller, Florissant, Mo., and Howard M. Lurton, Dow, Ill., assignors to Shell Oil Company, New York, N.Y., a corporation of Delaware
No Drawing. Filed Mar. 22, 1963, Ser. No. 267,341
12 Claims. (Cl. 252—34.7)

This invention relates to new and improved multifunctional liquid hydrocarbon composition such as gasoline, fuel oil, and mineral lubricating oil compositions. More particularly the invention is directed to above mentioned liquid hydrocarbon compositions possessing excellent corrosion (vapor and liquid) inhibiting properties as well as anti-stalling properties attributed to formation of ice on engine parts.

It is well known that corrosion due to chemical or mechanical means of engine parts results in inefficient engine operation and necessitates replacing of corroded parts, thus increasing the cost of effective engine operation. Corrosion of metal parts is particularly aggravated by ice formation on the throttle plate, carburetor and other engine parts which not only causes corrosion but engine stalling as well, which is an inconvenience and safety hazard.

It is an object of this invention to provide and improve liquid hydrocarbon compositions with effective corrosion inhibitors. Another object of this invention is to provide improved fuel (gasoline and fuel oil) compositions which prevent corrosion of metal parts. Still another object of this invention is to provide improved anti-clogging, anti-stalling and anti-corrosive fuel compositions. Also another object of this invention is to provide mineral lubricating oil compositions with improved vapor phase and liquid phase corrosion inhibiting properties. Other objects of this invention will be apparent from the following description of the invention.

It has now been found that improved corrosion inhibited liquid hydrocarbon compositions such as gasoline, fuel oil and mineral lubricating oil compositions can be rendered non-corrosive by addition thereto from about 0.0001% to about 2% and preferably from about 0.0005% to about 0.1% by weight of an oil-soluble additive mixture of (1) a C₆—36 alkyl or alkenyl succinic acid and (2) certain polyamine salts of C₆—36 alkyl or alkenyl succinic acid, the proportions of the two additives varying from about 1% to about 20% of the C₆—36 alkyl or alkenyl succinic acid and from about 80% to about 99% of the polyamine salt of C₆—36 alkyl or alkenyl succinic acid. By polyamine is meant an N-alkyl substituted alkylene polyamine and N-amino or N-hydroxy alkyl substituted imidazoline.

The amines of group (1) namely the N-alkylated polyamines include N-C₁₂—18 alkyl propylene diamine, N-C₁₂—18 alkyl ethylene diamine, N-C₁₂—18 alkenyl propylene diamine, N-C₁₂—18 alkenyl dipropylene triamine, octenyl diethylene triamine, decenyl triethylene tetraamine, octadecenyl propylene diamine, tetrapropenyl propylene diamine, and other polyamines of this type are commercially available under the trade name "Duomeens" and include Duomeen C

where R is derived from cocoanut, Duomeen S

2

where R is derived from soya, Duomeen T where R is derived from tallow; oxyalkylated Duomeen S

where R is heptadecenyl radical or polyamine such as Amine OLT (tetrapropenyl ethylene diamine) and the like.

The imidazolines are well known compounds which may be prepared by the methods described in Chemical Reviews, vol. 54, No. 4, August 1954 under the title "The Chemistry of Imidazoles" by Ferm and Riebsomer or they may be prepared by the method described in U.S. Patent 2,267,965. Examples of suitable compounds are 1-aminoethyl-2-undecyl imidazoline, 1-aminoethyl-2-heptadecenyl imidazoline, 1-aminoethyl-2-heptadecyl imidazoline, 1 - aminoisopropyl - 2 - heptadecyl-2-methyl imidazoline, 1-aminobutyl-2-pentadecyl imidazoline, 1-2-(2-aminoethyl)-aminoethyl-2-pentadecyl imidazoline. Amidoalkyl substituted imidazolines of this type are commercially available under the trade name of "Nalcamines" such as "Nalcamine G-32" which is 1-(2-aminoethyl)-2-n-C₁₂—18 alkyl imidazoline. Another preferred aminoalkyl imidazoline is prepared by reacting polyethylene polyamine with tall oil acids 125—250° C. to produce the aminoalkyl imidazoline. Other imidazolines are commercially available under the trade name Amine C, O and S and have the formula:

35 where R is principally undecyl (Amine C), heptadecenyl (Amine O) and heptadecenyl (Amine S) and the like.

The salts are simple to prepare and generally require admixing at from room temperature to about 150° F. one mole of the alkyl or alkenyl succinic acid with an equivalent amount of amine preferably in a neutral hydrocarbon solvent such as isoctane, benzene or xylene and allowing the mixture to interact which normally requires from 2 to 10 hours. The solvent, if desired, can be removed by suitable means such as distillation.

40 The C₆—36 alkyl and alkenyl succinic acids include octenyl, tetrapropenyl, heptadecenyl, octadecenyl, tetraisobutetyl, eicosenyl, heneicosyl, tricosenyl succinic acids.

45 For purpose of illustration, the following Example A is described:

One mole of "Duomeen C" was added while stirring to an equivalent amount of tetrapropenyl succinic acid in a xylene solvent at a rate slow enough to prevent a rise in temperature above 120° F. The reaction was stirred for 55 4—6 hours until the salt formation was complete after which the solvent was removed.

Other salts prepared by the method described include: (B) N-tetrapropenyl propylene diamine salt of heneicosyl succinic acid, (C) N-octadecenyl propylene diamine salt of heneicosyl succinic acid, (D) N-lauryl propylene diamine salt of tetrapropenyl succinic acid, (E) N-octyl diethylene triamine salt of heneicosyl succinic acid, (F) 1-hydroxyethyl-2-heptadecenyl imidazoline salt of heneicosyl succinic acid, (G) 1-aminoethyl-2-heptadecenyl imidazoline salt of tetrapropenyl succinic acid, (H) N-C₁₂—18 alkenyl dipropylene triamine salt of octadecenyl succinic acid, (I) Duomeen T-salt of oleyl succinic acid, (J) Duomeen S salt of ricinoleyl succinic acid, (K) 1-hydroxyethyl-2-heptadecenyl imidazoline salt of tetrapropenyl succinic acid and mixtures thereof.

The base carrier to which the additive mixture of the present invention is incorporated in small amount in order

to improve its properties includes light hydrocarbons e.g. isooctane, motor fuels, e.g. gasoline, which can be leaded or non-leaded, fuel oils such as domestic fuel oils, diesel fuel oils of various types as well as mineral lubricating oils of wide viscosity range such as SAE 5W through SAE 90 and higher.

Compositions of the present invention are illustrated by the following examples:

Example I

	Percent weight	10
Mixture of 90% of Ex. (A) salt and 10% tetra-		
propenyl succinic acid	0.001	

Gasoline Balance

Example II

	Percent weight	15
Mixture of 90% Ex. (K) salt and 10% tetra-		
propenyl succinic acid	0.001	

Gasoline Balance

Example III

	Percent weight	20
Mixture of 95% N-tetrapropenyl propylene di-		
amine salt of heneicosyl succinic acid and 5%		
of heneicosyl succinic acid	0.005	

Domestic Fuel Oil No. 2 Balance

Example IV

	Percent weight	25
Mixture of 95% of N-octoyl diethylene triamine		
salt of heneicosyl succinic acid and 5% of		
heneicosyl succinic acid	0.001	

Mineral lubricating oil (SAE 10) Balance

caps are then removed and 0.2 ml. of distilled water is placed in the dimple, the jars are recapped and are allowed to stand for five days (at $77 \pm 3^\circ$ F.) the specimens are then examined for rust. The test is run in quadruplicate and at least three of the four specimens must be free of rust in order to pass the test.

Examples I and II passed the Chrysler Corrosion Test whereas similar compositions in which the free tetrapropenyl succinic acid was omitted (Ex. I' and II') failed to pass this corrosion test.

Examples I to V were tested in the ASTM D-665-60 Synthetic Sea Water Rust Test (24 hours at 80° F.) and each of the Examples I-N passed the test whereas Example I' to V' (similar to Examples I-V but the free alkyl or alkenyl succinic acid was omitted) failed to pass the test.

Example III was tested in the Furnace Oil Rust Test which comprises visually examining for rust, steel panels treated with Example III composition for 16 hours and then exposing the steel panels to the same composition containing $\frac{1}{2}$ weight percent water. The panels are rated qualitatively by estimating the fraction of area covered with rust. Example III at even a lower concentration, 0.0015%, allowed no rust whereas Domestic Fuel Oil No. 2 + 0.0015% "Santolene CP," a Ba phenol sulfonate, allowed 5% rust and Neat Fuel Oil No. 2 allowed 27% rust.

The following compositions were also tested under conditions shown in Table I and the results were as follows:

TABLE I
[Base: Diesel fuel]

	Additive percent weight	Humidity ¹ Cabinet Life, Hrs.	BT-9 Humidity ² Corrosion Life, Hrs.	ASTM D-665 Turbine Oil Rust Test, 48 Hrs.
VI	1.8% weight 1-hydroxyethyl-2-heptadecenyl imidazoline salt of tetrapropenyl succinic acid.	144+	30	Pass, No rust.
VII	0.2% weight Tetrapropenyl succinic acid	144+	30	Do.
X	1.8% weight N-C ₁₂₋₁₈ alkenyl propylene diamine salt of tetrapropenyl succinic acid.	66		
Y	0.2% weight Tetrapropenyl succinic acid			
Y	1.8% weight 1-aminoethyl-2-heptadecenyl imidazoline salt of N-octyl sarcosine.			
Z	0.2% weight Capric acid			
Z	2% weight 1-aminoethyl-2-heptadecenyl imidazoline of capric acid.	75	25	Moderate rust.
Z	Base fuel	<30	<2	100% rust.

¹ Military specification JAN-H-792.

² IHC Humidity Cabinet type test in which polished steel rods, predipped in test fluid, are maintained at 80° F. in a humid, 90° F. atmosphere for 25 or more hours.

Example V

	Percent weight	55
Mixture of 90% of Ex. G salt and 10% of		
heneicosyl succinic acid	0.002	

Mineral lubricating oil (SAE 30) Balance

Compositions of the present invention (similar to Examples I and II but additive present at 0.01% wt.) reduced engine stalling by 20-40% compared to engines operating on neat gasoline under the same cold conditions of refrigeration which compared operating an automobile engine (Chevrolet) in a refrigerated chamber prone to form ice on the carburetor and other engine parts.

Compositions of the present invention were tested in the Chrysler Corrosion Test under the following conditions:

Specimens are $\frac{1}{2}$ " cold-roller sheet steel (SAE 1020) cut in the form of an equilateral triangle $1\frac{1}{2}$ " high with the corners turned down $\frac{3}{16}$ " and a dimple of $\frac{3}{8}$ " spherical radius in the center of the triangle. The specimens are freshly polished with Armour's 600A silicon carbide paper, cleaned with boiling benzene and boiled 1 minute in petroleum ether. They are then placed in 50 ml. of the test fuel in a $1\frac{1}{4}$ " diameter, 100 ml. wide-mount jar and allowed to stand at $77 \pm 3^\circ$ F. for one hour. The jar

Compositions of the present invention are also excellent vapor phase corrosion inhibitors protecting metals against corrosion for long periods of 6 months and more.

We claim as our invention:

1. A liquid hydrocarbon composition consisting essentially of a major amount of a liquid hydrocarbon and from about 0.001% to about 2% by weight of a mixture of (1) a C₆₋₃₆ hydrocarbyl succinic acid, said hydrocarbon radical being selected from the group consisting of C₆₋₃₆ alkyl and C₆₋₃₆ alkenyl radicals, and (2) a polyamine salt of a C₆₋₃₆ hydrocarbyl succinic acid, the hydrocarbyl radical being the same as in the free acid compound, the polyamine being selected from the group consisting of N-tetrapropenyl propylene diamine, N-octyl diethylene triamine, N-C₁₂₋₁₈ alkenyl propylene diamine, N-cocoanut propylene diamine, 1-aminoethyl-2-heptadecenyl imidazoline and 1-hydroxyethyl-2-heptadecenyl imidazoline; the free C₆₋₃₆ alkenyl or alkyl succinic acid constituting from about 1% to about 20% of the additive mixture in the balance, 99% to 80%, being the polyamine salt.

2. A liquid hydrocarbon composition consisting essentially of a major amount of a liquid hydrocarbon and from about 0.0001% to about 2% by weight of a mixture of tetrapropenyl succinic acid and N-C₁₂₋₁₈ alkenyl pro-

pylene diamine salt of tetrapropenyl succinic acid, the tetrapropenyl succinic acid constituting from about 1% to about 20% of the additive mixture and the balance 99%-80% being the diamine salt.

3. A liquid hydrocarbon composition consisting essentially of a major amount of a liquid hydrocarbon and from about 0.0001% to about 2% by weight of a mixture of tetrapropenyl succinic acid and N-aminoalkyl 2-heptadecenyl imidazoline salt of tetrapropenyl succinic acid, the tetrapropenyl succinic acid constituting from about 1% to about 20% of the additive mixture and the balance 99%-80% being the imidazoline salt.

4. A liquid hydrocarbon composition consisting essentially of a major amount of a liquid hydrocarbon and from about 0.0001% to about 2% by weight of a mixture of tetrapropenyl succinic acid and N-hydroxyalkyl 2-heptadecenyl imidazoline salt of tetrapropenyl succinic acid, the tetrapropenyl succinic acid constituting from about 1% to about 20% of the additive mixture and the balance 99%-80% being the imidazoline salt.

5. A gasoline composition consisting essentially of a major amount of gasoline and from about 0.0001% to about 2% by weight of a mixture of tetrapropenyl succinic acid and N-cocoanut propylene diamine salt of tetrapropenyl succinic acid the free acid constituting from about 1% to about 20% of the additive mixture and the balance 99%-80% being the diamine salt.

6. A gasoline composition consisting essentially of a major amount of gasoline and from about 0.0001% to about 2% by weight of a mixture of tetrapropenyl succinic acid and 1-hydroxyethyl-2-heptadecenyl imidazoline salt of tetrapropenyl succinic acid the free acid constituting from about 1% to about 20% of the additive mixture and the balance 99%-80% being the imidazoline salt.

7. A liquid hydrocarbon fuel oil composition consisting essentially of a major amount of fuel oil and from about 0.0001% to about 2% by weight of a mixture of tetrapropenyl succinic acid and N-cocoanut propylene diamine salt of tetrapropenyl succinic acid the free acid constituting from about 1% to about 20% of the additive mixture and the balance 99%-80% being the diamine salt.

8. A liquid hydrocarbon fuel oil consisting essentially of a major amount of fuel oil and from about 0.0001% to about 2% by weight of a mixture of tetrapropenyl succinic acid and 1-hydroxyethyl-2-heptadecenyl imidazoline

45

salt of tetrapropenyl succinic acid the free acid constituting from about 1% to about 20% of the additive mixture and the balance 99%-80% being the imidazoline salt.

9. A mineral lubricating oil composition consisting essentially of a major amount of mineral lubricating oil and from about 0.0001% to about 2% by weight of a mixture of tetrapropenyl succinic acid and N-cocoanut propylene diamine salt of tetrapropenyl succinic acid the free acid constituting from about 1% to about 20% of the additive mixture and the balance 99%-80% being the diamine salt.

10. A mineral lubricating oil composition consisting essentially of a major amount of mineral lubricating oil and from about 0.0001% to about 2% by weight of mixture of a tetrapropenyl succinic acid and 1-hydroxyethyl-2-heptadecenyl imidazoline salt of tetrapropenyl succinic acid the free acid constituting from about 1% to about 20% of the additive mixture and the balance 99%-80% being the imidazoline salt.

11. A liquid hydrocarbon fuel oil composition consisting essentially of a major amount of a liquid hydrocarbon fuel oil and containing about 0.001% of a mixture of 90% of N-C₆-36 alkyl diethylene triamine salt of tetrapropenyl succinic acid and 10% of tetrapropenyl succinic acid.

12. A liquid hydrocarbon fuel oil composition consisting essentially of a major amount of a liquid hydrocarbon fuel oil and containing about 0.001-0.005% of a mixture of 95% of N-tetrapropenyl propylene diamine salt of heneicosyl succinic acid and 5% of heneicosyl succinic acid.
